Attorney

UNITED STATES PATENT OFFICE.

ALEXANDER McMUNN, OF PHILADELPHIA, PENNSYLVANIA.

WARPING-MILL APPARATUS.

1,323,538.

Specification of Letters Patent. Patented Dec. 2, 1919.

Application filed December 3, 1918. Serial No. 265,101.

To all whom it may concern:

Be it known that I, ALEXANDER McMUNN, a citizen of the United States, residing in the city of Philadelphia, county of Philadelphia, and State of Pennsylvania, have invented certain Improvements in Warping-Mill Apparatus, of which the following is a specification.

My improvements are designed to secure greater output from warping mills with the employment of less labor, and to effect the spooling of the warps under even tension, thereby avoiding breakage of the threads, securing more even spooling, and increasing the quantity which may be wound upon a spool.

In the preferred form, my improvements are embodied in a reeling or spooling jack movable across the warping mill and driven therefrom through a channeled shaft connected by a belt with an epicyclic gear train which rotates the spool of the jack.

The accompanying drawings illustrate an embodiment of my invention, in which Figure 1 is a side elevation of warping mill apparatus embodying my improvements; Fig. 2 is a top plan view of the same with parts removed; and Fig. 3 is an enlarged sectional view of part of the reeling jack showing the epicyclic gears.

As shown in the drawings, the frame 1 has journaled therein the arbors 2 of the warp reel 2, the latter being provided with a driving band 3 through which it is rotated by the contact or friction wheel 4. The wheel 4 is fixed on a shaft 5 having on the end thereof the pulley 6 connected by the belt 7 with the main driving pulley 8.

A spooling jack or frame 9 (having its base slidably engaged in the ways 9^a) has journaled in latching bearings 9' thereof a shaft 10 on which is sleeved a warp winding spool or roll 11. A head 11' projects from the end of the spool and is adapted for engagement in the undercut slot 12' of a collar 12 keyed to the shaft 10, whereby the spool is readily fixed relatively to and dissociated from the shaft.

A wheel 13, journaled on a bearing 14 projecting from the frame 9, is provided with the internal circumferential gear teeth 15 meshing with a spur gear 16 fixed on the shaft 10.

A sheave 13' on the wheel 13 is connected by a belt 18 with a fluted shaft 19 journaled in the frame 1, the channels 19' of the shaft

securely positioning and affording a wide bearing surface for the belt 18 in a plurality of positions, so that the reeling jack may be moved across in front of the mill 60 to take off warps on different parts of the reel without affecting the driving mechanism.

The shaft 19 has fixed thereon a pulley 20 connected by a belt 21 with the idler 65 pulley 22 which is connected by a pulley 23 with the main driving pulley 8, the latter being controlled by a belt shifter 24 operable through the tension member 24' and treadle 25.

In operation, the jack is positioned in line with the warp to be taken off from the reel and the belt 18 engaged in an appropriate channel 19'. The bearings 9' are unlatched and the shaft 10 lifted for the insertion and 75 engagement of a spool 11. The end of the warp to be taken off the reel is connected with the spool, and upon the operation of the belt shifter 24 the reel 2 is rotated to unwind the warp and the spool 11 is rotated, 80 through the mechanism described, to automatically draw off the warp under proper tension and wind it upon the spool in uniform compact layers.

Having described my invention, I claim: 85

1. In apparatus of the character described, the combination of a warping mill having a reel and a shaft parallel therewith with a spooling jack having a spool movable across said reel, and driving means 90 connecting said mill and spool and comprising a belt adjustable along said shaft in accordance with the movement of said jack relatively to said reel.

2. In apparatus of the character de- 95 scribed, the combination of a warping mill having a reel, means for rotating said reel, and a channeled shaft connected with said means, with a spooling jack having a pulley, a belt connecting said shaft and pulley, 100 epicyclic gear mechanism connected with said pulley, and a spool operated by said gear mechanism.

3. In apparatus of the character de- 105 scribed, the combination of a warping mill having a reel, with a spooling jack having a journaled shaft, a spool, means for fixing said spool relatively to said shaft, a wheel on said shaft, a wheel having a circumferential part engaging said wheel first named, 110 and means for driving said second named wheel from said mill.

- 2
4. In apparatus of the character described, the combination of a warping mill having a reel, with a spooling jack having a spool provided with a journal seated in a bearing of said jack, epicyclic gear mechanism comprising a gear on the journal of said spool and a second gear wheel engag-

ing said first gear for rotating said journal and holding it in its seat, and means for driving said mechanism, said means being 10 adjustably connected with said mill.

In testimony whereof I have hereunto set my name this 30th day of November, 1918.

ALEX. McMUNN.
